GAS BURNER

Harry H. Dodge, Troy, N. Y., assignor, by mesne assignments, to Hoguet & Neary, New York, N. Y., a partnership consisting of Ramsay Hoguet, John F. Neary, and Daniel L. Morris

Application November 22, 1928, Serial No. 321,156

4 Claims. (Cl. 158—104)

This invention relates to a gas burner which is particularly adapted for use in heating house heating water or steam boilers or hot air furnaces.

I will illustrate, for the sake of convenience, the invention as applied to a water boiler such as used in household heating but the invention is not confined to such use.

In the drawings;

Figure 1 is a sectional view of the burner showing the same in place within a household boiler, the latter also being shown in section;

Figure 2 is a plan view of the burner; and

Figure 3 is a side elevation of the same.

In the drawings, the boiler is illustrated. This boiler includes the usual water container having an inner wall 1 and an outer wall 2 with the water space 3, within which inner wall 1 the fire pot 4 is formed. This boiler is supported upon a base 5 in the usual way, which base forms the ash pit 6, the front of which ash pit is normally open.

The device itself consists essentially of a plurality of burners arranged within the fire pot to produce a flame adjacent the inner wall of the boiler, means for creating an air curtain on the side of the flame remote from the inner wall of the boiler, means for mixing the air and gas to form a combustible mixture for the burners, and means for conducting the mixture under pressure to the burners and air under pressure to the air curtain producing means.

The embodiment of the device which I have illustrated in the drawings includes a manifold, which is preferably made in the form of a casting. This manifold which is illustrated in the drawings and which is for the purpose of supplying air and combustible mixture to four burners is provided with two mixing chambers 7, which are arranged above another pair 8 of mixing chambers.

In order that these two pairs of chambers may be supplied with gas a gas supply chamber 9 is formed which is of such an area that it communicates with all four of the mixing chambers 7 and 8. This gas supply chamber receives the gas through a port which is connected with a suitable source of supply.

In order that the upper pair of mixing chambers 7 may be supplied with air, the manifold is provided with an air supply chamber 10, which is of such an area that it communicates with both of the chambers 7. This air supply chamber receives its air from a suitable source of air under pressure through a port 10', such,

for instance, as from a blower of the character described in my copending application Serial No. 319,214, filed November 14, 1928, which blower I have here represented conventionally, and indicated by the reference character 11. The lower mixing chambers 8 are likewise supplied with air from an air supply chamber 12, which is also connected with the same source of supply of pressure air. So that the air chambers 10 and 12 may be supplied with air under pressure from the same common source 11 through the common inlet 10', I have provided the ends of the manifolds with covers 12'. These covers each have partitions 13' which create chambers 14' and 15'. The chamber 14' communicates with the ends of the gas chamber 9 and the chamber 15' communicates with the ends of the air chamber 10 and the air chamber 12. Thus air under pressure entering the inlet 10' will pass, by means of the chamber 15' to both of the chambers 10 and 12 for distribution to the mixing chamber.

It is of course desirable in supplying air to the mixture chambers 7 and 8 to regulate the quantity of air in relation to the quantity of gas which enters those chambers. For such regulation the passages between the air supply chamber 10 and the mixing chambers 7, between the air supply chamber 12 and the mixing chamber 8, are valve controlled. This control may, therefore, be by an adjustable valve—that is, one which may be manually adjusted or by a fixed valve, such as is shown in the drawings at 13, these valves 13 being in the form of perforated plates held in place by nuts 16' which plates may be supplanted by other similar plates having different port areas.

To supply gas from the chamber 9 to the mixing chambers 7 and 8, injectors are provided which injectors have centrally located passages 16, the effective opening of each of which is controlled by a perforated plate 17 in the end of the injector which, like the plates 13, may be changed. These injectors discharge into Venturi openings 18 from which the gaseous mixture is conducted.

Extending from the manifold and communicating with the Venturi openings 18, which extend from the upper chambers 7 are burner supporting arms 19 and from the Venturi openings, which communicate with the chambers 8, are arms 20. The arms 19 are provided with plates 21 on which the burners are adjustably supported, and each of these plates is provided with a slot 22 which communicates with the bore 23

of the arm, which bore in turn communicates with the chamber 7 through the Venturi opening 18. Thus the slot 22 in the plate 21 is supplied with a combustible mixture under pressure.

5 Each of these plates 21 is also provided with a slot 24 which slot is supplied with air under pressure in the following manner:

A pipe 25 communicates with this slot 24 and extends to a port 26 in the manifold, which port 10 communicates with the air supply chamber 10 and is valve controlled at 27. Thus the air which passes to the slot 24 through the pipe 25 is taken from the air supply at a point in advance of the mixing chambers 7, so that the measured quantity of air entering the mixing chambers is not affected by the flow of air from the supply chamber 10 to the pipe 25.

For the other pair of burners a similar arrangement is provided—that is to say, each of the supports 20 has a plate 28 at the end thereof and a duct 29 communicating with the adjacent Venturi opening 18 and hence with the mixing chamber 8. This duct 29 likewise communicates with a slot in the plate 28 corresponding with the slot 22 in the plate 21. An air supply pipe 30 communicates with a slot in the plate 28 corresponding with the slot 24 in the plate 21, and this air supply pipe communicates with the air supply chamber 12 through a valve controlled 25 port 31, similar to the port 26 which I have described, but through a by-pass 32.

The burner head of the form shown in the drawings which is particularly adapted for use with the plates 21 is similar to that described in my copending application, Serial No. 321,155 filed November 22, 1928, but it is to be understood that such a burner head, as described in my copending application Serial No. 321,154 filed November 22, 1928 may be used, in which 40 event, of course, the form of the supports 19 and 20 and of the air supply pipes 25 and 30 will be changed to that shown in said last mentioned application. However, this will necessitate no change in the manifold.

45 Describing the burner head which is illustrated in these drawings, and taking only one of these for the purpose of description, it includes a casting which is adjustable on the plate 21 and held in its adjusted position by a bolt 33. The slot 22 in this head communicates with the combustible mixture chamber 34, irrespective of the adjusted position of the burner on the plate 21, and this chamber 34 which is tortuous and has a baffle, such as described in one of the above referred 50 to applications, communicates with a burner tip 36 having a slot 37 therein for the escape of the combustible mixture to a burning position. The burner is also provided with an air chamber 38 which communicates with a slot 24 in the plate 21, irrespective of the position of the burner. This chamber 38 discharges the air adjacent the burner tip 36 and between the tip and a baffle 39, which directs the air toward the flame above the tip 36.

60 65 As the other burners are of substantially the same construction I need not describe the construction of each.

As this device is adapted for use in standard household boilers by mere insertion in the fire pot and ash pit, it is of course desirable to have the burners adjustable as I have described them, so that they may be adapted to various inside 80 diameters of boilers and so that the position of the burners may be adjusted in relation to the inner wall of the boiler.

Moreover, should it be desirable, as the size 85 of the boiler increases the number of burners may likewise be increased and this, of course, will necessitate an increase in the number of supporting arms and air supply pipes which extend from the manifold.

Another feature of my invention which is of 90 importance is the provision of means for supporting the device within the ash pit and the construction of this means in such manner that it may be used by mere adjustment to support the device within boilers of different types. This means includes a plurality of adjustable standards 95 49 adjacent the ends of the arms 20 and adjustable supporting standards 50 beneath the manifold.

What I claim is:

1. In a manifold, a plurality of mixing chambers, a gas supply chamber common to all of said mixing chambers, air supply chambers, each common to only certain of said mixing chambers, ducts for the escape of the gaseous mixture from the mixing chambers, and a duct for the escape 105 of air from each of said air supply chambers directly to the atmosphere.

2. In a manifold, a plurality of mixing chambers, a gas supply chamber common to all of said mixing chambers, air supply chambers, each common to only certain of said mixing chambers, ducts for the escape of the gaseous mixture from the mixing chambers, a duct for the escape of air 110 from each of said air supply chambers directly to the atmosphere, and means for supplying air 115 under pressure to said air supply chambers.

3. The combination with a burner for combustible mixture and an air passage associated therewith, of a supply manifold for said burner, said manifold having a plurality of mixing chambers, a gas supply chamber common to all of said mixing chambers, air supply chambers each common to only certain of said mixing chambers, a duct extending from the mixing chambers to the burner, and a duct extending from each of the air 125 chambers to the air passage.

4. The combination with a burner for combustible mixture and an air passage associated therewith, of a supply manifold for said burner, said manifold having a plurality of mixing chambers, a gas supply chamber common to all of said mixing chambers, air supply chambers each common to only certain of said mixing chambers, a duct extending from the mixing chambers to the burner, air ducts extending from each of the 130 air chambers to the air passage, and means for supplying air under pressure to said air chambers.

HARRY H. DODGE.
